UNITED STATES PATENT OFFICE.

HORACE W. HORNE AND JAMES HENDERSON, OF HAVERHILL, ASSIGNEES
TO JAMES W. BROOKS, TRUSTEE, OF CAMBRIDGE, MASSACHUSETTS.

HEEL-NAILING MACHINE.

SPECIFICATION forming part of Letters Patent No. 389,077, dated September 4, 1888.

Application filed June 22, 1887. Serial No. 242,096. (No model.)

To all whom it may concern:

Be it known that we, HORACE W. HORNE and JAMES HENDERSON, of Haverhill, in the county of Essex and State of Massachusetts, 5 have invented certain new and useful Improvements in Heel-Nailing Machines, of which the following is a specification.

This invention relates to heel-nailing machines employing a nail-holding block having 10 holes arranged to receive a gang of nails and hold them in the order in which they are placed in the heel, a gang of drivers which work loosely in said block and force the nails from the block into the heel, and a top-lift plate 15 or spanker which is brought into position over said block after the heel has been attached and forces a top lift laid upon it onto the projecting ends of the nails after the same have been inserted in the heel, the drivers being 20 made so short that the nails inserted by them are left protruding sufficiently to enable them to hold the top lift.

The top-lift plate or spanker is pivoted to the nail-holding block, and is moved away 25 from the top of said block during the operation of driving the nails, and is moved over the block after the nails are driven, so as to cover the nail-holding orifices in said block, and present a smooth surface while attaching 30 the top lift.

This invention relates to mechanism for attaching heels to boots and shoes, and is an improvement upon that shown and described in United States Patent No. 166,765, dated 35 August 17, 1875, it having for its object to provide the top-lift plate shown in said patent and used in connection with the heel support or plate with a holding device or catch, by which the top lift may be held in position 40 upon the said top-lift plate.

The holding device or catch is herein shown as a spring-actuated slide movable in a guide on the top-lift plate, the said slide normally pressing upon one face of the top lift to retain it in position upon the top-lift plate, and adapted to be thereafter removed from the said top lift, as will be described.

To this end our invention consists, in a heel-

nailing machine, in the combination of the nail-holding block, a horizontally-swinging 50 top-lift plate, and a catch or holding device, substantially as described, on the top-lift plate adapted to overlap and engage the top lift positively, substantially as set forth.

Also, our invention further consists, in a 55 heel-nailing machine, in the combination of the nail-holding block, a horizontally-swinging top-lift plate, a catch or holding device, substantially as described, on the top-lift plate adapted to overlap and engage the top lift 60 positively, and automatic mechanism for releasing the top lift, substantially as described.

Of the accompanying drawings, forming a part of this specification, Figure 1 represents a top view of a nail-holding block and top-lift 65 plate, together with our improvements, the said plate being shown as turned out from its operative position. Fig. 2 represents a top view of the same, the top-lift plate being in place. Fig. 3 represents a side view with the 70 top-lift plate in the position shown in Fig. 2. Fig. 4 represents a sectional view showing the top-lift holding device or catch displaced to release the top lift. Figs. 5, 6, and 7 represent modifications.

The same letters of reference indicate the 75 same parts in all the figures.

In the drawings, *a* represents the nail-holding block, having a gang of orifices arranged to hold the series of nails which attach a heel. 80 The block is supported by a standard, *s*, on a bed or plate, *t*, which will be raised and lowered, as usual, by mechanism provided for that purpose, the block being adapted to slide on said standard down to the bed *t* and to be normally raised from said bed, as shown in Figs. 1 and 3, by a spring in the socket in which the standard slides. The drivers *b b* are placed loosely in said orifices and rest at their lower ends on the bed or plate *t*.

The top-lift plate *e*, pivoted by a stud, *f*, to the block *a*, is surmounted in usual manner by a spring, *g*, which normally acts to turn the top lift into position over the block *a*, as shown in Figs. 2 and 3.

In the operation of the machine the top-lift

plate is moved to one side, as shown in Fig. 1, and the heel is placed on the upper surface of the block, a gang of nails having been previously placed in the orifices of the latter. The 5 shoe placed on an iron last is then moved into place over the block, and thereafter the parts are moved in usual manner to cause the drivers to force the nails outwardly from the orifices of the block into the heel. The drivers 10 are of such length that they do not entirely insert the nails, but leave their heads projecting. The plate *t* is then depressed, so as to leave room between it and the block *a* and the heel for the insertion of the top-lift plate with 15 the top lift thereon. The depression of the block releases the top-lift plate from the heel and enables the spring *g* to turn the said plate into position over the block *a*, as shown in Figs. 2 and 3.

20 The devices and mode of operation thus far described are not new with us.

In carrying out our invention we provide the top-lift plate with a top-lift engaging device or catch adapted to secure or confine the 25 top lift to the said top-lift plate while the latter is out of position, as in Fig. 1, so that when the block and drivers are depressed and the top-lift plate is acted upon by its spring *g* to turn it into position over the block *a* it will 30 carry the top lift with it into position to be applied to the heel. We prefer to employ for this purpose a dog or catch, 2, which, as shown in Figs. 1 to 4, is adapted to slide in a slot, 3, in the raised portion *v*, against which the breast 35 of the top lift bears. One end of said clamp is formed to bear upon the upper surface of a top lift, 4, while the latter is being carried to and placed in its proper position on the heel, and is pressed downwardly upon said lift by 40 a spring, 5, with sufficient force to hold the lift and prevent it from being thrown edge-wise out of place by the motion of the top-lift plate when the latter is swinging to place, and by the abrupt stoppage of the said plate by 45 the stud *w*, which arrests it in its operative position.

The catch 2 is adapted to tilt or rock on a fulcrum, 6, so that its lift-holding end may be raised by the depression of its opposite end by 50 the finger of the operator. In the catch is an orifice, 7, which, when the catch is moved forward to hold the lift 4, as shown in Figs. 1, 2, and 3, is located a little forward of and out of line with a steady-pin, 8, which is attached to the base *t*, and enters a socket in 55 the top-lift plate when the block bears on the base *t*, the office of said steady-pin in machines in use prior to our invention being to prevent the top-lift plate from turning on its 60 pivot by the pressure of the heel-trimming knife against it.

We make the steady-pin slightly longer than heretofore, and round off or bevel its upper end, so that when it reaches the catch 65 2 its reduced extremity will first enter the orifice 7, and by pressure against one edge of

said orifice will force the catch back, as shown in Fig. 4, until it is removed from the top lift. It will be seen, therefore, that the operator places the top lift on the top-lift plate 70 while the latter is in the position shown in Fig. 1, and engages the catch 2 with it, and that the catch holds the top lift on the said plate until the latter has been carried to place, the catch being afterward moved back automatically by the steady-pin, as above described. Our invention is not, however, limited to the sliding catch shown, as we may employ one or more brads, *u*, (see Figs. 5 to 7,) as the means for engaging the top lift with 80 the said plate, said brads being placed close to the shoulder *v*, against which the breast of the top lift bears, and projecting upwardly so as to enter the grain-surface of the top lift. (See Fig. 7.) The top lift is readily forced 85 onto the brads, and is held in place thereby with sufficient firmness to prevent the lift from being thrown edgewise out of place by the motion of the spanker and by its abrupt stoppage. The brads are located so near the 90 breast of the heel, however, that the marks made by them are in that portion of the leather that is removed by the breasting operation, so that the heel is not defaced.

The brads may be arranged horizontally in 95 the breast-supporting shoulder *v* of the top-lift plate, as shown in Fig. 5, in which case it is preferable to pivot them to the top-lift plate, so that they can swing upwardly when the heel is being removed, and will not therefore be wrenching or broken by the removal of the heel. The brads when thus arranged may be held in their normal positions by 100 springs *m*.

Another modification is shown in Fig. 6, in 105 which two spring-arms are secured to a plate, which is arranged to be moved back by the steady-pin in the same manner that the catch 2 is moved. Said arms are arranged to grasp the opposite edges of the top lift near the 110 breast, as shown.

It will be seen that by our improvement the expense of special mechanism for supplying the top lifts is avoided. The top lifts may be engaged with the top-lift plate by the attendant who places the heel-blanks in position, there being sufficient time for this operation while the nails are being driven, so that the cost of running the machine is not increased. 115

We claim—

1. In a heel-nailing machine, the combination of the nail-holding block, a horizontally swinging top-lift plate, and a catch or holding device, substantially as described, on the top-lift plate, adapted to overlap and engage 125 the top lift positively, substantially as set forth.

2. In a heel-nailing machine, the combination of the nail-holding block, a horizontally swinging top-lift plate, a catch or holding device, substantially as described, on the top-lift plate adapted to overlap and engage the 130

top lift positively, and automatic mechanism for releasing the top lift, substantially as described.

3. The combination of the nail-holding block, the spring-impelled spanker pivoted thereto, a sliding clamp or top-lift holder on said spanker, and the pin 8, arranged to displace said clamp or holder, as set forth.

In testimony whereof we have signed our

names to this specification, in the presence of 10 two subscribing witnesses, this 17th day of June, A. D. 1887.

HORACE W. HORNE.
JAMES HENDERSON.
